ADJUSTABLE SHEET SEPARATOR
MECHANISM

Elmer W. Belluche and Frank R. Belluche, Racine, Wis., assignors to The Christensen Machine Company, Racine, Wis., a corporation of Wisconsin.

Application June 14, 1948; Serial No. 32,768

12 Claims. (Cl. 271—18)

1

This invention relates to feeders for printing machines, and refers more particularly to the sheet separator mechanism of such feeders, by which the topmost sheet of a pile of sheets is separated from the pile and advanced toward feed off mechanism at the front of the pile.

In practice, a pile of paper sheets to be fed to a printing machine or the like by the feeder is supported on a platform with the front edge of the pile adjacent to the feed off mechanism of the feeder and with the topmost sheet of the pile in predetermined elevational relationship with respect to the feed off mechanism.

Since the platform upon which the pile of sheets rests is automatically elevated periodically during operation of the feeder, no difficulty has been experienced in maintaining the pile of sheets in proper relationship to the feed off mechanism.

However, considerable difficulty is experienced in properly locating the top rear of the pile with respect to the separator mechanism to enable the separator instrumentalities to function properly in the separation of the topmost sheet from the pile. Differences in elevation between the top of the pile at the front and back thereof is most noticeable when the sheets supported on the platform have been printed one or more times and especially when the printing is largely confined to areas of the sheets located near the front or back of the pile. Under these circumstances, the pile tends to bulge upwardly at the inked or printed portions of the sheets due to the many superimposed thicknesses of ink, while unprinted portions tend to lie perfectly flat.

Assuming a condition where previously printed sheets are supported on the platform of the feeder and where the printing was confined chiefly to the front portions of the sheets, it will be apparent that although the platform may be adjusted to bring the front of the pile to the proper elevation with respect to the feed off mechanism, the rear of the pile will be at an elevation substantially lower than that of the front of the pile and consequently will not be in proper elevational relationship with respect to the sheet separator mechanism which operates on the rear portion of the pile.

In order to compensate for the differences in height between the front and rear portions of the pile it was necessary previously to insert wedges and/or spacers between the sheets of the pile at a number of locations in the pile to bring the rear thereof to a proper elevation permitting efficient use of the separating instrumentalities.

2

The use of wedges and spacers, of course, is objectionable since it is a relatively difficult and time consuming undertaking to insert spacers or drive wedges into place in the pile, and often causes damage to many of the sheets in the pile. Moreover, a wedged-up pile of sheets must be given periodic attention for the removal of wedges rendered inoperative as the height of the pile decreases during operation of the feeder. Usually, such removal of wedges and spacers requires stoppage of the feeder and the press supplied thereby.

With this objection in mind, it is an object of this invention to provide sheet feeders with a separating unit readily adjustable up and down relative to the feed off mechanism to enable proper elevational positioning of the separating mechanism with respect to the topmost sheet of the pile at the rear thereof regardless of inequalities in the height of the pile as between its front and rear portions.

Another object of this invention resides in the provision of separator mechanism of the character described which is not only adjustable vertically relative to the feed off mechanism of the feeder, but which is provided with improved means for effecting lateral adjustment of the separator instrumentalities.

Still another object of this invention resides in the provision of improved means for automatically elevating the platform upon which the pile of sheets is supported to maintain the topmost sheet of the pile at a predetermined elevation best suited for feeding of the sheets.

With the above and other objects in view, which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention constructed according to the best mode so far devised for the practical application of the principles thereof, and in which:

Figure 1 is a diagrammatic side elevational view showing the height relationships between the separator and feed off mechanisms of a sheet feeder with respect to the topmost sheet of a pile having greater height at the front edge of the pile than at the back edge of the pile;

Figure 2 is a similar diagrammatic view illustrating the steps that were taken in the past to

bring the top of the pile of sheets to a uniform height at its front and back edges;

Figure 3 is a diagrammatic view illustrating the manner in which inequalities in height at the front and back edges of the pile are compensated for by the adjustable separator mechanism of this invention;

Figure 4 is more or less diagrammatic perspective view of a portion of the separator unit illustrating the manner in which it is adjustable, both vertically and laterally;

Figures 5 and 6 are side elevational views of the separator mechanism illustrating the same in two different positions of vertical adjustment; and

Figure 7 is a diagrammatic view similar to Figure 3 but illustrating the manner in which the platform for the pile of sheets is automatically elevated as the height of the pile diminishes to maintain the top of the pile at a predetermined elevation.

Referring now more particularly to the accompanying drawings and particularly to the diagrams of Figures 1 and 2 illustrating conventional practice, the numeral 5 designates the platform of a pile type sheet feeder. The platform is adapted to support a pile of paper sheets 6 at the rear of the feeder and at an elevation such as to bring the topmost sheet of the pile substantially tangent to the upper cylindrical surface of a feed roll 7 forming part of the feed off mechanism generally designated 8 located at the front edge of the pile.

Sheet separator mechanism generally designated 10 is carried by the feeder to act upon the topmost sheet of the pile at the rear thereof, and the separator mechanism includes the usual combing wheels, and suckers and blowers not shown, which operate upon the rear portion of the topmost sheet of the pile to separate the same from the pile and effect advance of such sheet to the feed off mechanism 8.

When the forward edge of the topmost sheet is advanced over the feed roll 7 a drop roll 11 is brought down onto the sheet so that rotation of the feed roll 7 propels the sheet forwardly off the pile.

In all sheet feeders of the type herein concerned it is customary to maintain the platform 5 at a height so that the elevation of the front of the pile of sheets at all times bears a predetermined relationship to the feed off mechanism 8, and when clean or unprinted sheets are supported on the platform the pile of sheets has substantially uniform height throughout. In other words, the adjustment of the platform to bring the front of the pile to its proper elevation for feeding the topmost sheet of the pile into the feed off mechanism 8 automatically disposes the rear portion of the pile at the proper elevation for operation of the separator instrumentalities thereon.

In the past the separating unit of sheet feeders of the type herein concerned has been supported from the feeder at a fixed elevation relative to the feed off mechanism 8, and while this arrangement proved satisfactory for the feeding of clean or unprinted sheets, or for the feeding of clean sheets to multicolor presses, it gave rise to serious objections in the event the feeder was used with single color presses requiring the sheets to be fed through the press a number of times for the printing of different colors thereon.

In cases where the printing was confined chiefly to the front portions of the sheets a pile

of such printed sheets to be run through the press another time invariably was higher at its front edge than at its back edge, as seen in Figure 1 of the drawings, and the separating instrumentalities operable upon the rear portions of the sheets of the pile were sometimes incapable of effecting their proper functions because of the insufficient elevation of the rear of the pile.

10 In practice, therefore, it has been necessary to insert wedges 12 into the rear and side edges of the pile at different elevations to lift the rear portion of the pile up to the elevation at which the separating instrumentalities properly engaged the topmost sheet of the pile for the performance of their functions.

15 In the present invention the separator unit 15 is readily adjustable vertically relative to the feed off mechanism 8 to enable proper positioning of the separating instrumentalities of the unit with respect to the sheets at the rear of the pile despite inequalities in the height of the pile at the front and rear portions thereof. Hence, as seen in Figure 3, which illustrates a case where the topmost sheet of the pile is at a lower elevation at the rear of the pile than at the front thereof, the separating mechanism may be lowered as a unit to the elevation required for proper engagement of the separating instrumentalities 30 with the topmost sheet of the pile.

20 The separating unit comprises a pair of separating heads 16 and 17 upon which the usual separating instrumentalities including combing wheels, and suckers and blowers not shown, are mounted.

25 Each head comprises an inner and outer mechanism housing 18 and 19, respectively, joined together in spaced apart relationship and each mounted for sliding motion lengthwise along a pair of adjacent supporting shafts 20 and 21 forming part of a carriage 22 for the separator mechanism.

30 The carriage 22 as stated comprises the pair of shafts 20 and 21, and these shafts have their opposite end portions received in end frames 23 so as to be held in spaced apart parallel relationship by the end frames. Although the shafts 20 and 21 hold the end frames spaced apart a distance substantially corresponding to the spacing 35 of the side frames 25 of the feeder which extend horizontally rearwardly over the pile of sheets to be fed, the foremost shaft 21 is journaled for rotation in suitable bearings in the end frames 23 while the rearmost shaft 20 is fixed against turning.

35 The opposite ends of the shafts project from the outer sides of the end frames and have similar levers 26 and 27, respectively, mounted thereon. The levers 26 are free to rock upon the projecting ends of the fixed shaft 20 while the levers 27 are fixed on the shaft 21 to rotate or oscillate therewith. The levers have their arms extending downwardly and the lower ends of the arms of each pair of levers are joined by a link 28. The 40 points of connection between the links and the lever arms are spaced the same distance from the axis of the levers in each case, and the links hold the levers in parallel relationship so as to produce parallelogram linkage at each end of the carriage.

45 The entire separator unit is supported from the supporting or side frames 25 of the feeder by means of the parallelogram linkage described, inasmuch as the links 28 are seated upon the top surfaces of the supporting frames and slidably

lengthwise thereof. Hence, swinging of the linkage to bring the levers toward a vertical position from either side of vertical effects bodily lifting of the separator unit relative to the supporting frames 25 and consequently relatively to the feed off mechanism 8 to enable accurate positioning of the separating instrumentalities (not shown) with relation to the topmost sheet at the rear of the pile.

Adjustment of the height of the separating unit relative to the pile is effected by means of a hand wheel 30 fixed on the rear end of an adjusting screw 31. This adjusting screw has its rear end portion journaled in a bearing 32 carried by a bracket 33 connected across the supporting shafts 23 and 24 between the separator heads 16 and 17, and the forward end of the adjusting screw is threaded into a nut 34 pivotally carried by the upstanding arm of a lever 35 fixed on the rotatable shaft 21.

Inasmuch as the adjusting screw 31 is held against axial sliding motion by the bearing 32, it will be apparent that rotation of the hand wheel 30 imparts oscillatory motion to the shaft 21 in a direction depending upon the direction of rotation of the hand wheel. The oscillation thus imparted to the shaft 21, of course, is simultaneously transmitted to the parallelogram linkage on the opposite ends of the supporting shafts to effect either raising or lowering of the separator unit.

Up and down adjustment of the separator unit is constrained to a vertical translating motion by the transverse pinion shaft 37 which provides for longitudinal adjustment of the separator unit.

The shaft 37 is more or less conventional in most feeders and has pinions 38 mounted on its opposite ends (only one of which is shown) meshing with fixed horizontal racks 39 supported from the opposite supporting frames 25. In the present case the shaft 37 is received in vertical slots 40 opening to the undersides of the end frames 23 of the separator unit so that rotation of the shaft in one direction or the other propels the separator unit backwardly or forwardly of the feeder to enable adjustment of the separator unit at the proper point with relation to the rear edge of the sheets on the pile.

Hence, it will be apparent that this shaft 37 which is embraced by the sides of the slots 40 in the end frames 23 guides the separator unit for vertical up and down motion in response to swinging of the parallelogram linkage in one direction or the other.

Transverse adjustment of each of the separator heads 16 and 17 is effected by rotation of a hand wheel 42 fixed to a nut 43 encircling the shaft 20 and having internal screw threads cooperating with screw threads 44 on the exterior of the shaft 20.

The nut for each separator head has its opposite ends rotatably received in suitable bearings 45 carried by the mechanism housings of the heads, with each nut spanning the space between its housings as shown best in Figure 4. The bearings 45 in the separator heads preclude endwise motion of the nut relative to the heads so that rotation of each of the nuts by its hand wheel 42 causes its mechanism head to be drawn either inwardly or outwardly laterally of the separator unit.

Once the platform 5 for supporting the pile of sheets has been adjusted to bring the top of the pile to the proper elevation with relation to the feed off mechanism 8, the height of the pile is automatically maintained by means which pe-

riodically lifts the platform as sheets are fed off the pile. The pile elevating means comprises an electric motor 50 preferably drivingly connected through a suitable gear reduction, not shown, with the chains 51 by which the platform 5 is suspended. These chains depend from suitable sprockets in the conventional manner and since the manner of connecting the platform with the motor forms no part of this invention it is sufficient to point out that the motor is of the reversible type so that operation thereof in one direction effects lifting of the platform 5 while operation in the opposite direction effects lowering of the platform.

As the height of the pile of sheets diminishes during successive feeding of the sheets by the feeder, the electric motor is put into operation periodically for brief intervals of time to bring the pile to the proper elevation for the feed off operation. This is accomplished in the present invention by means of a feeler 52 carried by a pair of vertically spaced levers 53 and 54 for endwise up and down motion toward and from the top of the pile of sheets at the rear of the pile.

The feeler may be carried by either one of the supporting heads but in the present case is shown connected with the innermost mechanism housing 18 of the head 16. The levers 53 and 54 are pivotally supported on the inner side of the housing 18 for rocking motion about transverse axes spaced one above the other and with their arms 55 and 56, respectively, which connect with the feeler extending substantially horizontally rearwardly.

35 A cam 58 exposed at the exterior of the housing 18 but driven by mechanism within the housing cooperates with a roller 59 on another arm 60 of the lowermost lever 54 to impart rocking motion to both levers through the feeler and to cause the feeler to be lifted up and down.

Downward travel of the feeler, of course, is limited by the engagement of its lower end with the pile of sheets, and as long as the top of the pile is at an elevation best suited for efficient operation of the feeding instrumentalities, no elevational adjustment of the platform is necessary. Upon decrease in the height of the pile by successive feeding of sheets therefrom, the feeler 52 descends farther and farther each time it is lowered by the cam 58.

Sometime before the height of the pile decreases an extent interfering with efficient operation of the feeding instrumentalities, downward motion of the feeler toward the top of the pile 55 effects closure of a normally open switch 62 mounted on the mechanism housing 18 above an arm 63 on the lever 53 opposite the arm 55 thereof.

The actuator 64 of the switch projects downwardly to be engaged by the arm 63 of lever 53 at this time to effect closure of the switch by the upward movement of the arm, and energization of the electric motor 50 in a direction to effect elevation of the platform 5.

65 Hence, whenever the switch 62 is closed by the arm 63 of the lever 53 in consequence to descent of the feeler beyond a predetermined level the motor is set into operation and the platform begins to rise slowly to return the top of the pile to the proper height.

Since the feeler is lifted up and down periodically it will be seen that the motor operates intermittently to lift the platform to the proper elevation. When the height of the pile is back to normal the pile limits downward descent of the

feeler and prevents the arm 63 of lever 53 from closing the switch, and further elevation of the platform ceases.

The electrical connections between the switch and the motor are illustrated in Figure 7, and since these connections are deemed obvious no detailed explanation thereof is required. It is sufficient to note that a manually operable reversing switch 66 is provided. The switch 66 is in parallel with the switch 62 so that the platform may be raised or lowered at the will of the operator. The switch 66, of course, is provided mainly for the purpose of initially lifting the platform, and for lowering the platform after all the sheets have been fed therefrom.

Attention is directed to the fact that the feeler rod 52 is adjustably connected as at 67 to the lever arms 55 and 56. Vertical adjustment of the feeler, however, is necessary only at the time of assembly of the separator unit, and when once adjusted, proper height spacing between the separator instrumentalities and the top of the pile is assured by reason of the fact the feeler is carried bodily with the separator unit during any vertical adjustment thereof.

In the present invention, the switch 62 is mounted upon a slide 70 which may be moved horizontally forwardly or rearwardly and locked in place upon the mechanism housing 18 by means of screws 71. Consequently, the switch 62 is bodily adjustable toward and from the axis of the lever 53 so as to enable earlier or later actuation of the switch by the arm 63 of the lever 53.

If the switch is set substantially close to the axis of the lever it will initiate operation of the motor 50 at less frequent intervals than when the switch is set further away from the axis of the lever and toward the outer end of the arm 63 thereon.

From the foregoing description taken in connection with the accompanying drawings it will be readily apparent to those skilled in the art that the vertically adjustable separator unit of this invention materially facilitates "setting up" of the feeder to which it is attached; that exceedingly simple but efficient means is provided for automatically controlling the height of the pile of sheets acted upon by the separator instrumentalities; and that lateral adjustment of the separator instrumentalities is effected in a novel manner utilizing one of the transverse supporting elements of the separator unit.

What we claim as our invention is:

1. In a sheet feeder of the character described: a pair of spaced elevated supporting frames at the rear of the feeder to lie at opposite sides of a pile of sheets to be handled by the feeder; a sheet separator unit extending transversely across the rear of the feeder between said supporting frames and above the rear portion of said pile of sheets, said separator unit including a transverse supporting shaft, and separator instrumentalities operable upon the topmost sheet of the pile; means for supporting said separator unit from the supporting frames at any of a number of elevations with respect to said frames, comprising a lever fixed on each end of said transverse shaft, and a connection between each lever and its adjacent frame by which rocking motion of the supporting shaft in one direction effects bodily lifting of the separator unit; and means connected with said transverse shaft for imparting rocking motion thereto and for holding the shaft in any of a number of positions of rotation.

2. In a sheet feeder of the character de-

scribed: a pair of spaced elevated supporting frames at the rear of the feeder to lie at opposite sides of a pile of sheets to be handled by the feeder; a separator unit including sheet separating instrumentalities operable upon the sheets of said pile; means supporting said separator unit from the supporting frames with the separator unit extending transversely across the rear of the feeder between said supporting frames and above the rear portion of the pile of sheets, said supporting means including levers pivotally mounted on the separator unit adjacent to the supporting frames, and connections between said levers and the supporting frames adjacent thereto to whereby swinging motion of the levers in one direction effects bodily elevation of the separator unit relative to said supporting frames; and means for imparting swinging motion to said levers and for holding the same in any desired position of angular adjustment.

3. In a sheet feeder of the character described: a pair of spaced elevated supporting frames at the rear of the feeder to lie at opposite sides of a pile of sheets to be handled by the feeder; a separator unit including a pair of end frames spaced apart a distance substantially corresponding to the spacing of the supporting frames and sheet separator instrumentalities connected with said end frames to be supported thereby and operable upon the sheets of said pile; means for supporting said separator unit from the supporting frames with the unit extending transversely across the rear of the feeder between said supporting frames and with each of said end frames adjacent to one of said supporting frames, said means including a pair of levers pivotally connected with each of said end frames, and a link joining the ends of each pair of levers and slidably received on the adjacent supporting frame so that simultaneous swinging of each pair of levers in the same direction effects bodily lifting of the separator unit relative to the supporting frames; and means for imparting simultaneous swinging motion to said levers and for holding the same in any of a number of positions of angular adjustment.

4. The sheet feeder set forth in claim 3 further characterized by the provision of means for constraining up and down adjustment of the separator unit to substantially vertical translating motion.

5. In a sheet feeder of the character described: a pair of spaced elevated supporting frames at the rear of the feeder to lie at opposite sides of a pile of sheets to be handled by the feeder; separator means operable upon the sheets of the pile; a carriage for said separator means comprising a pair of end frames spaced apart a distance substantially corresponding to the spacing between the supporting frames, and a pair of shafts connected between said end frames and joining the same together, said shafts being held by the end frames in spaced apart parallel relationship, one of said shafts being rotatably journaled in said end frames, and the other of said shafts being non-rotatably connected with said end frames; means mounting said separator means upon said shafts for sliding motion along the length thereof; a connection between said fixed shaft and the separator means for holding the separator means in any of a number of different positions along the length of said shafts; and means supporting said separator unit from the supporting frames with the unit extending transversely across the rear of the feeder between

said supporting frames and above the rear portion of the pile of sheets, said means including parallelogram linkage connected between each of said shafts and the supporting frame adjacent thereto to enable elevational adjustment of the carriage and the separator means thereon relative to the supporting frames.

6. In a sheet feeder of the character described: a pair of spaced elevated supporting frames at the rear of the feeder to lie at opposite sides of a pile of sheets to be handled by the feeder; a sheet separator unit extending transversely across said supporting frames, said separator unit comprising a pair of supporting shafts, and end frames connected across said shafts at each end thereof to hold the same in spaced parallel relationship, with one of said shafts journaled for rotation in said end frames and with the other of said shafts fixed against rotation, said separator unit including separator means supported jointly by said shafts for sliding motion transversely of the feeder toward and from the opposite supporting frames thereof; a screw connection between said fixed shaft and the separator means providing for transverse adjustment of the separator means relative to the supporting frames of the feeder and to a pile of sheets between said supporting frames; a lever fixed on each end of said rotatable shaft for rotation therewith; a lever loose on each end of said fixed shaft; said levers having arms substantially the same length; and a link pivotally connecting the arms of the levers at each end of said shafts, said links resting on the supporting frames so as to provide for up and down adjustment of the separator unit relative to the supporting frames upon swinging of the levers and links in one direction or the other; and means for imparting swinging motion to said levers and links and for holding the linkage in any of a number of desired positions of adjustment, said means comprising a bracket connected across said shafts, another lever fixed to said rotatable shaft, and a screw mounted on said bracket and threaded into a nut carried by said other lever for imparting rocking motion in opposite directions to said rotatable shaft through said other lever fixed thereon.

7. In a sheet feeder, the combination of: an elevatable platform adapted to support a pile of paper sheets; means adjacent to the front edge of the pile for feeding off the topmost sheet of the pile, said means having a fixed elevation and requiring the top of the pile to be in a predetermined elevational relationship thereto; a separator unit including separating mechanism operable upon the rear edge portion of the pile of sheets and adapted to separate the topmost sheet from the pile and to effect advance of said topmost sheet to the feed off mechanism at the front of the pile; a feeler mounted on said separator unit for up and down motion and operable to feel for the top of the pile; means for raising the platform including a motor; a switch for connecting said motor with a source of E. M. F.; a connection between the feeler and said switch whereby downward motion of the feeler beyond a predetermined level at which the separating mechanism best operates upon the pile effects closure of the switch to initiate operation of the motor and raising of the platform; and means mounting the separator unit and the feeler for vertical adjustment in unison relative to the feed off means to enable initial positioning of the separator mechanism and the feeler in proper elevational relationship to the top of the pile at that

10
5 part thereof acted upon by the feeler and the separating mechanism.
8. A separator unit for sheet feeders comprising: an elongated carriage adapted to be carried by the supporting structure of the feeder, said carriage including a screw shaft extending transversely across the rear of the feeder; adjustable means on said screw shaft connected between the carriage and the supporting structure of the feeder for supporting the carriage from said supporting structure at any of a number of levels above the top of a pile of sheets beneath the carriage; separator means operable upon the rear of a pile of sheets beneath the carriage; means including said screw shaft mounting the separator means on the carriage for lateral sliding motion lengthwise of said shaft; a tubular part encircling said screw shaft and having screw threads on its interior cooperating with the threads on the shaft so that rotation of said tubular part causes the same to be drawn along the shaft in one direction or the other; and a connection between said tubular part and said separator means whereby the separator means is driven longitudinally along the screw shaft with the tubular part to different positions of lateral adjustment on the carriage.

9. In a sheet feeder of the character described: spaced elevated side frames at the rear of the feeder; a separator unit including a separator head having instrumentalities operable upon the rear portion of a pile of sheets of paper to be handled by the feeder; means mounting said separator unit on said side frames for bodily up and down adjusting motion relative to said frames and to the top of a pile of sheets being handled by the feeder; and a feeler carried by said separator head for up and down motion relative thereto and adapted to feel for the top of a pile 30
35
40
45 of sheets being handled by the feeder, said feeler being bodily movable with the separator unit to different positions of vertical adjustment thereof so as to at all times have a predetermined positional relation to the separator instrumentalities on said head.

10. In a sheet feeder of the character described: a pair of spaced elevated side frames at the rear of the feeder to lie at opposite sides of a pile of sheets to be handled by the feeder; a carriage extending transversely across the rear of the feeder between said frames and above said pile of sheets; separator instrumentalities mounted on said carriage and operable upon the topmost sheet of the pile; means for adjustably supporting said carriage from said side frames at any of a number of elevations with respect to said frames, including an element pivotally supported on said carriage adjacent to each of said frames, and connections between said elements and the frames adjacent thereto for translating pivotal motion of said elements in one direction into bodily elevation of the carriage relative to the side frames; an actuator connected with said elements for rocking the same in unison, said actuator including means for holding said elements in any of a number of positions of rotation.

11. In a sheet feeder of the character described: a pair of spaced elevated side frames at the rear of the feeder to lie at opposite sides of a pile of sheets to be handled by the feeder; a sheet separator unit extending transversely across the rear of the feeder between said side frames and above the rear portion of said pile of sheets, said separator unit including a rotatable supporting

11

shaft extending transversely between said frames, and separator instrumentalities operable upon the topmost sheet of the pile; means for adjustably supporting said separator unit from the side frames at any of a number of elevations with respect to said frames, comprising connections between said shaft and each side frame operable to translate rotative motion of the shaft in one direction into bodily elevation of the separator unit relative to the side frames; and means connected with said transverse shaft for imparting rocking motion thereto and for holding the shaft in any desired position of rotation.

12. In a sheet feeder, the combination of: an elevatable platform adapted to support a pile of sheets; means adjacent to the front edge of the pile for feeding off the topmost sheet thereof; a separator unit including separating mechanism operable upon the pile of sheets and adapted to separate the topmost sheet from the pile and to effect advance of said topmost sheet to the feed off mechanism at the front of the pile; a feeler adapted to move up and down onto and off of the top of the pile; means for raising the platform including a motor; means mounting said feeler on the separator unit for said up and down motion of the feeler; an arm pivotally mounted on said separator unit and connected with the feeler

12

so as to swing back and forth on its pivot in consequence to up and down motion of the feeler; a switch for controlling operation of said motor; means mounting said switch on the separator unit adjacent to said arm so that the switch is closed by the arm in consequence to downward motion of the feeler beyond a predetermined level at which the separating mechanism best operates upon the pile, to thereby initiate operation of the motor and effect raising of the platform; and means for adjusting the position of said switch lengthwise of said arm whereby the frequency of operation of said motor may be varied.
